UNITED STATES PATENT OFFICE.

CHARLES S. BURTON, OF OAK PARK, ILLINOIS.

FUEL-FEEDING DEVICE FOR INTERNAL-COMBUSTION ENGINES.

1,296,364.

Specification of Letters Patent.

Patented Mar. 4, 1919.

Application filed July 9, 1917. Serial No. 179,580.

To all whom it may concern:

Be it known that I, CHARLES S. BURTON, a citizen of the United States, residing at Oak Park, in the county of Cook and State of Illinois, have invented new and useful Improvements in Fuel-Feeding Devices for Internal-Combustion Engines, of which the following is a specification, reference being had to the accompanying drawings, forming a part thereof.

The purpose of this invention is to provide an improved device of the nature of a vacuum fuel feed for an internal combustion engine. It consists in the elements and features of construction shown and described as indicated in the claims.

In the drawings:

Figure 1 is a side elevation showing a portion of an engine of an automobile equipped with this invention.

Fig. 2 is a partly sectional side elevation showing in conventional form a vacuum fuel feed device, and in vertical section the low level main supply tank and liquid fuel duct connections therein which constitute the distinguishing feature of this invention.

Fig. 3 is a diagrammatic view showing the invention applied directly to the float chamber of the carburetor without the invention of the usual "vacuum tank",—the float chamber being shown in axial section.

The engine intake manifold, 1, is shown connected with a vacuum fuel feed device of familiar form comprising a supplemental reservoir, 2, for supplying the carburetor, and a so-called vacuum chamber, 3, into which the liquid fuel is lifted by the suction of the engine from a low level main tank, 4, and supplied by gravity to a reservoir, 40 which is the reserve chamber 2 of the vacuum feed device, the suction for so lifting the liquid being produced by a suction connection by means of the tube, 5, leading from the vacuum tank to the engine manifold.

As thus far described, the structure is of familiar form and detail. The features constituting the present invention are designed to overcome a defect which has been experienced in the use of vacuum fuel feed devices, arising from the fact that under certain conditions of service of the engine, the suction produced by the engine is liable to be inadequate to lift the liquid from the main low level tank to the vacuum chamber, and when such conditions continue for considerable time, as when ascending a long

slope requiring the engine to run with a wide-open throttle for a considerable time, the reserve fuel accumulated in the reserve chamber, 2, becomes exhausted before it can be re-supplied from the main tank. This defect is overcome in the present device by an expedient which amounts substantially to causing the suction for lifting the liquid from the low tank to operate upon the liquid in the low tank in such a manner as to atomize it by aspiration so that it is not thereafter lifted as a liquid column, but rather as a liquid freighted air column, or at least a highly aerated liquid column which can be sustained by the atmospheric pressure operating on the surface of the liquid in the main tank to a much greater height than that pressure would sustain a solid liquid column. This aspiration or aeration is effected by providing the pipe, 7, which connects the low level tank, 4, with the vacuum chamber, 3, with a mouth-piece in said tank, 4, shown at 7^a, being of comparatively widely-extended, funnel-shape, preferably having its margin serrated or provided with a multiplicity of slits, 7^a, said mouth-piece being connected flexibly, as by a flexible tube, 8, with the pipe, 7, of which it forms in effect a continuation, and being supported by a float, 9, adapted with respect to the weight of the mouth-piece and the flexible connection to hold the mouth-piece with its serrated or slotted marginal edge, dipping the points of the teeth, at least, in the surface of the liquid in the tank. The result of this construction is that the suction operating through the mouth-piece, drawing in the air close to the surface of the liquid in sub-divided streams or jets, entrains the liquid in a spray and so carries an intermixture of liquid, which may be described as aerated liquid, or liquid-freighted air, according to the proportions of the intermixture, which will vary with several conditions, such as temperature, force of the suction, and depth of submersion of the edge of the mouth-piece. The result will be attained, even though the depth mouth-piece should be submerged more deeply than the depth of the slits, 7^a, when the suction is adequate to pull in the air through the trap which will be formed by such submersion, and such submersion will occur in cases of high suction, the partial vacuum produced under the expanded mouth-piece tending to cause it to be depressed, against the resist-

ance caused by the buoyancy of the float, so that when adjusted originally with the serrations only partly submerged, upon high suction the submergence may include the whole length of the slits forming the serrations, but as indicated without defeating the operation of the device, because the same high suction will pull the air in through the liquid trap thus formed.

10 In order that this mixture may not be drawn over from the vacuum chamber, 3, directly into the manifold, to so large an extent as to over-enrich the explosive charge furnished to the manifold through the carbureter, there is provided at the discharge end of the pipe, 7, in the vacuum chamber, 3, a baffle plate, 12, against which the mixture discharges which causes precipitation mechanically of the liquid contained in the 15 discharge, leaving the air drawn in only moderately charged with the fuel vapor, the liquid thus precipitated accumulating in the vacuum chamber, 3, and operating in the usual manner of this class of devices. Instead of the serrations in the edge of the mouth-piece, 7^b, the mouth-piece may have a finely perforated area as shown at 7^c in Fig. 3. Either form of mouth-piece may be used whether the connection is made to the 20 float chamber or to the vacuum chamber of an auxiliary vacuum feed tank.

The expedient above described for lightening the liquid column leading from the main tank, makes it possible to dispense with the customary supplemental elevated "vacuum tank" so called, and conduct the liquid fuel supply directly to a reservoir which constitutes the carbureter float chamber, and such a structure is shown in Fig. 3, 25 wherein said float chamber, 15, is connected with the main tank, 4, by the pipe, 7, which discharges herein against a baffle formed by

the top of the chamber causing mechanical precipitation of the liquid particle carried in suspension. In my claims I intend the term "reservoir" to apply equally to the reservoir afforded by the carbureter float chamber when the pipe, 7, leads directly to that chamber and to the reservoir afforded by the vacuum feed tank when said pipe, 7, leads to such tank.

I claim:—

1. In a vacuum fuel feeding device in combination with a low level main supply tank, a reservoir at a higher level, a duct 45 leading from the low level tank to said reservoir, and means for inducing suction therethrough; a horizontally-extended mouth-piece for said duct in the low level tank, and means for positioning said mouth-piece with its intake margin substantially as the surface of the liquid in the tank.

2. In a structure such as defined in claim 1, the margin of the mouth-piece being serrated.

3. In a structure such as defined in claim 1, the means for positioning the mouth-piece at the liquid surface, consisting of a float which carries the mouth-piece and a flexible tube connecting said mouth-piece with the 70 connection of the duct to the tank.

4. In a structure such as defined in claim 1, a baffle in the reservoir against which the duct discharges for precipitating liquid from the mixed air and liquid discharged.

5. In a structure such as defined in claim 4 foregoing, the discharge connection in the reservoir being positioned for directing the discharge against the wall of the reservoir whereby such wall constitutes the baffle.

In testimony whereof, I have hereunto set my hand at Chicago, Illinois, this 27th day of June, 1917.

CHARLES S. BURTON.
